UNITED STATES PATENT OFFICE.

DAVID SCHULER, OF MEADVILLE, PENNSYLVANIA, ASSIGNOR TO THE SPIRELLA COMPANY, OF MEADVILLE, PENNSYLVANIA, A CORPORATION OF PENNSYLVANIA.

GARMENT-STAY.

1,108,251.

Specification of Letters Patent.

Patented Aug. 25, 1914.

Application filed January 2, 1909. Serial No. 470,593.

To all whom it may concern:

Be it known that I, DAVID SCHULER, a resident of Meadville, in the county of Crawford and State of Pennsylvania, have 5 invented a new and useful Improvement in Garment-Stays, of which the following is a specification.

This invention relates to garment stays or stiffeners, and more particularly to stays 10 for corsets and the like formed from wire.

The object of the invention is to produce a stay or stiffener for corsets and other garments which will take the place of a whalebone and which is constructed of wire 15 bent to shape and in a manner that it may be bent laterally or edgewise, or even twisted and which possesses a high degree of flexibility and elasticity and which cannot readily be broken or take a permanent bend or 20 set.

The invention consists of a stay or structure as hereinafter described and claimed.

In the accompanying drawing Figure 1 is a face view of the stay formed from a 25 single wire; Fig. 2 is a cross-section through the same; and Fig. 3 is a face view showing a modification formed of two wires.

In Fig. 1 the stay is formed from a continuous piece of spring wire 1 bent laterally 30 back and forth to form a series of loops or eyes 2 which are arranged diagonally across the face of the stay, thus forming a flat structure of wire composed of a series of loops or eyes with the wire forming the 35 same extending diagonally across the width of the stay. As shown in Fig. 1 the loops or eyes are circular at their outer closed ends and taper toward their open ends, but with the closed ends sufficiently wide so that 40 each side of each loop or eye overlaps the side of the adjoining loop or eye. Consequently each loop or eye is in position to take a bearing on both sides on the adjacent loops or eyes so that when the stay is bent 45 flatwise the loops or eyes bear on each other and thus transfer the stresses from any given loop or eye to the adjacent loop or eye, and cause the stay to bend on a large circle, and preventing the bending stresses 50 from concentrating at any point or few points and overcoming the tendency of the metal to crystallize. The consequence is that a stay so formed does not readily break.

By having the loops or eyes extending 55 diagonally across the width of the stay I

utilize both the torsional and the bending strength of the wire, the transversely extending portions or crossings of the wire, such as the parts 4, when the stay is bent 60 flatwise being placed under torsion by reason of their transverse trend and also being subjected to a bending movement by reason of their longitudinal trend. The result is that the stay possesses a very high 65 degree of elasticity and stiffness for the size 60 of the wire employed, so that it is possible to form a stay having the required elasticity and stiffness from comparatively light wire.

In order to increase the rigidity of the stay, and particularly to make it more rigid 70 when bending in one direction than in the other, the intermediate portions of the wire are deflected from the plane of the stay, as indicated at 6, Fig. 2, or in other words the stay is slightly concaved on one side. 75 This gives the stay a greater rigidity against bending toward the convex side than toward the concave side and peculiarly adapts the stay for garment stiffeners in which the bending stresses are mostly outwardly, so 80 that it is only necessary to place the concave side inwardly to secure considerably greater rigidity against outward bending movements which are the ones to be resisted, than toward bending in the opposite direction. 85

Fig. 3 shows a modification in which the stay is composed of two wires instead of a single one, every other loop, such as those marked 7, being formed in one wire, while 90 the alternate loops 7^a are formed in the other wire. Each loop, however, has its sides overlapping the two adjoining loops, exactly as in Fig. 1, the only difference being that instead of having the several loops 95 in succession formed in one wire, they are alternately formed in different wires. The same effect against bending stresses is obtained in this case as in the form shown in Fig. 1. This form also is slightly concaved 100 transversely.

A tip 8 will be applied to the ends of the stay to give finish, and the stay will be inserted in the garment in the usual fabric casing or pocket.

What I claim is:

1. A garment stay consisting of wire bent to form a series of oppositely disposed loops or eyes forming the edges of the stay and having the connecting portions extending 110

diagonally across the stay, all said connecting portions being inclined in the same direction with reference to the longitudinal axis of the stay, and each side of each loop 5 overlapping the adjacent loop.

2. A garment stay consisting of wire bent to form a series of oppositely disposed loops forming the edges of the stay and with the connecting portions extending diagonally 10 across the stay, all said connecting portions being inclined in the same direction with reference to the longitudinal axis of the stay and being bent to concave the stay on one side, each side of each loop overlapping 15 an adjacent loop.

3. A garment stay consisting of wire bent to form a series of oppositely disposed loops or eyes forming the edges of the stay and having the connecting portions extending 20 diagonally across the stay, all said connect-

ing portions being inclined in the same direction with relation to the longitudinal axis of the stay, each side of each loop overlapping the adjacent loop, and said wire having no crossing or contacting portions 25 other than these due to such overlapping.

4. A wire garment stay, formed of a single wire, bent in alternately progressive loops, each extending laterally entirely 30 across the width of the stay, and disposed at an acute or oblique angle to the longitudinal axis of the stay, substantially as shown and set forth.

In testimony whereof, I have hereunto set my hand.

DAVID SCHULER.
